R.H. Cole,

Making Bolts

No 18534.

Patented Nov. 3, 1857.

UNITED STATES PATENT OFFICE.

R. H. COLE, OF ST. LOUIS, MISSOURI.

MACHINE FOR MAKING BOLTS.

Specification of Letters Patent No. 18,534, dated November 3, 1857.

To all whom it may concern:

Be it known that I, RICHARD H. COLE, of the city of St. Louis and State of Missouri, have invented a new and Improved 5 Machine for Making Metallic Bolts; and I do hereby declare that the following is a full, clear, and exact description of the same, reference being had to the annexed drawing, making a part of this specification, in 10 which—

Figure 3 is a plan, Fig. 2 a front elevation, and Figs. 11 and 12 show a section through the line A', as seen from opposite ends of the machine, Fig. 11 showing an 15 end elevation of the gripping jaws, together with the knife and mode of operating it, and Fig. 12 a front elevation of the die or heading box F. Fig. 1 is a side elevation of the slides D and E showing their relative position with each other together with the working parts attached to them and also the 20 relative position of the cams on the shafts B and D.

The nature of my invention consists— 25 first in pressing the head on the bolt in a moving die, or heading box against a yielding tool by the motion of the bolt instead of the tool. Second in devising means for pointing the bolt and cutting it from the 30 bar in a single operation. Third in gripping the bolt between a fixed and yielding jaw—so as to keep the machine from breaking in case anything should get between the said jaw.

35 The construction and operation whereby I effect the objects above pointed out will be understood from the following description of the aforesaid drawing—similar letters represent corresponding parts on the different figures. I first make the frame A A of the form shown on the drawing, with the plumber blocks B B cast on it. In the inside of the frame and on each side of it, I cast the ribs C C, and in the top of them 40 I plane square grooves, in which I insert strips of steel as shown at V, which I make adjustable by means of the adjusting screws e e shown at Fig. 11. I then make the slides D and E. Fig. 10 shows an elevation, and Fig. 5 a plan of the slide D. Fig. 9 is an elevation and Fig. 4 a plan of the slide E. These slides I make to work in the frame on the ribs or foot pieces c c as shown at Figs. 11 and 12. I grip the bolt 45 between a pair of jaws, one of which I cast

on the slide D as shown at T, and the other I cast in a separate piece in the form of a slide as shown at S Fig. 7. In the top of the slide D I make a recess and in it I place the jaw, so as to work at right angles with the slide D, and correspond with the jaw T, cast on that slide. The sliding jaw is held in position by means of the angular foot P, and the gib Q, which is adjusted by the screws r. r. On the bottom of the slide 60 D and at right angles with it, I cast the two lugs G G and between them I place the slide H and secure it by means of the gib I as shown at Fig. 1. This slide I make with an incline plane on one of its ends and in the under side of it I insert two round balls—shown at J Figs. 1 and 11—which take their bearing on the bottom of the frame as shown at K Fig. 11. A side elevation and a plan of this slide is shown at 70 H H Fig. 10. On the under side of the slide D I cast a pair of lugs, to receive; and form a center for the bar to vibrate around as shown by the dotted lines at M. In the end of this bar and in the under side of it 80 I insert a roller, which is acted upon by the incline plane K. On the end of the slide H, and directly over this roller in the top of the bar, I cut a circular groove and in it I set the lower end of the knife N which 85 works up through the slide D at the back end of the gripping jaws, so as to cut the bolt from the bar after the jaws have gripped it.

The lugs forming the center for the bar L 90 to vibrate around are set apart a distance equal to the difference in the length of the different bolts, so that the position of the bar L can be altered by moving it backward or forward, as the case may require, and by 95 putting washers against its side to hold it in the given position. And as the knife N works through a slot in the slide it can also be moved backward or forward, so as to keep its position on the bar L.

In the top of the slide D and at the back of the knife I cut a long groove and in it I place the adjusting slide O so as to come flush with the top of the slide, and in the bottom of this groove I cut a slot through the slide big enough to receive a bolt and allow it to slide freely from one end to the other. So that when it is desired to move the knife and bar L—one way or the other—the slide O, may be advanced, or moved back 105 110

so as to keep its position against the back of the knife, whereby it will be supported while the head is being pressed on the bolt.

The knife N is pressed up and made to 5 cut off the bolt by the action of the incline-plane K and is brought down by the action of the spring H shown in dotted lines, Fig. 1.

I make the tools for gripping the bolt as 10 shown at Figs. 7 and 8. U is a piece of steel, turned and bored to the form shown, and inserted in the jaw, where it is secured by means of a key, as shown, and H' is likewise a piece of steel turned and bored as shown, and inserted in the piece U and 15 keyed there. Each size bolt requires a different set of tools, because the knife has to work against the end of the tool H' and the tool U has to be cut away to let the knife up to its position as shown.

20 The inside of the tool H' is made as shown at Z Figs. 7 and 10—that is—with the form that receives the bolt countersunk from the forward end and with the countersink filed out from the center downward, 25 so that the tools in coming together will form a point on the top side of the bolt, or in other words will form half of the required point on the bolt, and in doing so will slightly bend it downward in the recess 30 cut in the bottom side of the tool, so that by the action of the knife in cutting the bolt will be brought back to a straight line, and the remaining half of the required point formed on the bolt by an offset on the knife 35 which has a form in it to correspond with the countersink in the top side of the tools H, as shown at Z, Fig. 10.

In the end of the slide E, I insert the 40 crotch a made in the form shown on the drawing at Fig. 6 and secure it by means of jam nuts, as shown, and in the end of each branch of this crotch, I insert two rollers, one on each side as shown in dotted lines v v Fig. 3, and on the outside of each 45 branch of the said crotch I bolt a sliding cam as shown at d one of which acts on a pin fixed in the jaw S, and the other on a similar pin fixed in the slide H, so that when the machine is in motion the cams d d 50 will act on their respective pins (one of which is shown at b) and throw back the jaw S and the slide H. On the back, or out end of the jaw S, I make an incline, plane or sliding cam as shown at j and directly 55 under this inclination, or cam, and on the slide H at i I make another identical in every respect with the first, and in the same relative position, with the crotch roller. Now it will be seen by reference to 60 Fig. 6 that the bottom branch of the crotch is the shortest, so that in advancing the top roller will strike the inclination j and close the jaw S, by the time the roller in the lower branch of the crotch begins to 65 act on the inclination i of the slide H, thus

causing the knife N to cut the bolt from the bar and point it, as soon as the jaw S has gripped it. The outside roller in the top branch of the aforesaid crotch, takes its bearing against the spring X, and the corresponding roller in the lower branch takes its bearing against the rib C as shown at Fig. 11.

The spring X has its bearing against a rib cast on the frame for that purpose, as shown at h and the strap passing around it is continued, so as to form a bolt by which the spring is attached, and "loaded" to the the said rig. The object in making the top roller work against a yielding bearing is to prevent the machine from breaking in case there should get too much iron between the jaws, or in case the bar should not be fairly entered in the jaws. On the top of the slide E I lay the spring Y which has its bearing against the bar U, to which it is also bound by means of the strap bolt W, and against the spring Y and to the strap W, I secure the heading tool g, loosely, so as to vibrate in any direction. I cast the 90 recess J in the top of the slide E, to receive the bottom of the strap W, and in the bottom of this recess I cast another, so as to allow the ends of the strap m to clear the slide when in operation, and I also 95 cut a circular groove across the recess J to receive the roller n upon which the spring Y takes its bearing. On the end of the slide E at t, I place the die box F, which consists of a cylinder with both of its ends bored out, so as to leave a partition in the center and so as to receive the end of the slide in one 100 end and the dies f f f in the other.

The dies are made of the form shown on the drawing with their angles to lap passed 105 the center in each direction by which the hole in the center may be made larger or smaller, as the case may require, by means of the adjusting screws k k. The dies are held down on the bottom of the box by the screws s s s s, the heads of which take their bearing against eccentric pieces let in the dies, so that when it is desired to adjust the dies in either direction these screws are removed, and the dies adjusted to the desired 110 position, and the eccentric pieces turned to correspond with the holes in the bottom of the dies. The screws are then replaced and the dies are ready for use. On the shaft D I place the two cams, made in the form shown on the drawing, the small cam carries the slide forward and the large carries it back, and they are so constructed as to work against each other, that is—the one advances as fast as the other recedes—and so 115 as to carry the slide forward in four sixteenths, and back in three sixteenths of the revolution of the cam, thus causing the slide to remain in the backward position during nine sixteenths of the revolutions of the cam. 120 125 130

On the shaft B I also place two cams of the form shown to work against each other precisely as in the case of those on the shaft D. Each of these cams work against rollers placed in brass or iron boxes as shown. These boxes I make adjustable by means of keys, shown in dotted lines at N' Fig. 1 so that when it is desired to make bolts of different sizes the relative position of the slides D 5 and E may be altered, by putting the packing pieces (shown at 7 in dotted lines Fig. 1) behind the opposite boxes whereby the slide E will be thrown back and the slide D forward, thus causing the tool g to reach 10 farther through the die box, and so as to leave a narrower space between the end of the tool and the heading jaw, which will make the head on the bolt correspondingly less in thickness. Let the shaft B and D 15 revolve in the direction of the arrows; it will be seen by the position of the cams on the two shafts that when the cam B is on its extreme forward throw the cam D will just commence to act, and it will also be seen that 20 the cams on the shaft B have one inch more throw than those on the shaft D, so that when the machine is in operation the cam D follows the cam B as fast as it recedes until it arrives at its extreme forward throw; it 25 then returns, and the cam B continues to recede the remaining inch of its throw carrying the die box back on the heading tool whereby the bolt head is displaced from the die in which it was formed.

30 Let us suppose the machine in operation and suppose both cams on their backward throws as seen at Fig. 1. The slides D and E will then be at their greatest distance from each other. The bar of iron is then shoved 35 through the jaws (which are now open) against the tool g which is at rest. The cam B then commences to advance and carry the die box forward on the tool g, and the crotch a is also carried forward against the 40 inclination j on the jaw s so as to close it, and as soon as the jaw is closed the lower branch of the crotch commences to act on the inclination i on the slide H which causes the incline plane K to press the knife N up 45 so as to cut off the bolt from the bar. The bolt is now cut off and pointed, and the 50

knife is against the end of the bolt; and the face of the die box is up against the end of the gripping jaws. The cam D now commences to advance and the cam B to recede, 55 thus keeping the face of the gripping jaws against the face of the die box until the cam D has arrived on its extreme forward throw. The jaw then returns to its backward position, while the cam B continues to recede 60 and carry the die box back on the heading tool and off of the bolt head, which then drops to the ground finished. The first operation then is to grip the bar; the second is to cut off the bolt and point it, and the 65 third is to carry it forward against a yielding punch whereby the head is pressed on it in a die box, which being removed by the action of the cam, completes the operation and releases the bolt from the machine. 70

What I therefore claim as my invention and desire to secure by Letters Patent is—

1. Pressing the head on the bolt in a moving die box or die, and against a yielding tool or support substantially as set forth by 75 the motion of the bolt instead of the tool substantially as described.

2. And I also claim the combination of the spring X, the crotch a and the jaw S, so that the crotch a or its substitute in pressing the jaw S forward shall act against a 80 yielding medium for the purpose specified.

3. And I also claim the internal construction of the gripping tools H as shown at z, whereby each of the said tools in closing 85 shall form one fourth of the point on the bolt, thus making half of the point when closed.

4. And I claim finishing the point on the bolt, that is, completing it, by an offset made 90 on the side of the knife N having a form in it to correspond with the form in the end of the tools H, the said offset to be below the cutting edge of the knife a distance equal to the diameter of the point of the bolt when 95 finished, so as to make the point of bolt like the frustum of a cone.

R. H. COLE.
